UNITED STATES PATENT OFFICE.

JAMES D. NEGUS, OF DOUGLAS, WYOMING.

RAILWAY-ROAD-BED CONSTRUCTION.

1,262,548.

Specification of Letters Patent.

Patented Apr. 9, 1918.

Application filed July 18, 1917. Serial No. 181,328.

To all whom it may concern:

Be it known that I, JAMES DELOS NEGUS, a citizen of the United States, residing at Douglas, in the county of Converse and 5 State of Wyoming, have invented new and useful Improvements in Railway-Road-Bed Construction, of which the following is a specification.

This invention relates to improvements in 10 the construction of railway road beds, the object of the invention being to provide a road bed having a water proof covering for the surface of the bed proper, as well as the major portions of the ties, together with all 15 embankments, excavations, drainage ditches, etc., alongside the road bed, and which water-proof covering will be so constructed as to facilitate the drainage off of the water, thereby keeping the road bed continually 20 dry and diminishing the rusting of the rails and other metallic parts of the road structure, and at the same time preventing rotting of the ties and the undermining or 25 loosening of the soil from the action of water and the results incident thereto.

A further object of the invention is to provide a road bed structure which will reduce the cost of repairs and up-keep of the tracks, etc., will maintain the alinement of 30 the rails and the established grade to prevent derailments and other accidents, which will reduce the amount of dust deposited and set into motion by the travel of a passing train, which will prevent the growth of 35 grass, weeds, etc., in the road bed, which will obviate liability of danger of fire reaching and attacking the ties and which will insure greater resiliency of the rails and greater comfort in travel thereover, with a 40 final gain in the cost of construction and maintenance of the road bed and track notwithstanding any primary increased cost under some conditions.

With these and other objects in view, the 45 invention consists of the features of construction, combination and arrangement of parts hereinafter fully described and claimed, reference being had to the accompanying drawings in which:—

50 Figure 1 is a top plan view of a section of a railway road bed and track embodying the principles of my invention.

Fig. 2 is a vertical longitudinal section taken centrally between the track rails as 55 indicated by the line 2—2 of Fig. 1.

Fig. 3 is a vertical transverse section taken on a plane between ties, as indicated by the line 3—3 of Fig. 1.

Fig. 4 is a vertical transverse section on the line 4—4 of Fig. 1, taken on the line 60 of one of the ties.

Fig. 5 is a section on the line 5—5 of Fig. 1.

Referring to the drawings, 1 designates the earth base or other foundation, 2 the 65 ties and 3 the track rails of the road bed and track construction, the rails being secured to the ties in the ordinary or any preferred manner, as by the use of spikes or other similar fastenings 4.

The ties 2, which may be of wood or metal, but preferably of wood, are embedded in the foundation 1 up to a point adjacent to the tops of the ties, the latter projecting just sufficiently above the general line of the surface of the trackway to support the rails in a sufficiently elevated position. As shown, the entire road bed, consisting of the surface of the foundation 1 between the rails and ties and laterally beyond the same to the 70 base of the embankment forming the road bed is provided with a covering 5 of water-proof material. This covering 5 is preferably and ordinarily from one to two 75 inches in depth and consists of a fine concrete cement, composed of one part of good hydraulic cement and three parts of good silica sand or cement applied and compacted by the use of an ordinary cement gun or in any suitable manner. This layer of 80 concrete covers the surface of the earth throughout the entire area of the road bed and the sides of the ties up to the level of the rails, thus preventing the water from reaching the sides of the ties and rotting 85 the same. The water-proof surface also prevents the rain or other water from reaching any part of the road bed, thus preventing the earth from becoming loosened and softened up, or of being washed away or undermined in any manner, whereby a solid and compact roadway will at all times be 90 secured.

For the purpose of protecting the tops of the ties and sealing the openings formed by the rail spikes or fastenings, the exposed surfaces of the ties may be coated with tar, pitch or any other suitable like water-proofing coating, which may be fired in about the spikes to prevent the entrance of moisture to 110

the spike holes, whereby these surfaces will be protected from moisture and the general action of the elements.

In Fig. 5 which is a section on the line 5—5 of Fig. 1, I have shown the covering above the ties as being thicker at the edge portions, and the upper surface of the portion of covering between the ties meeting the upper portions of the ties proper. The 10 covering above the ties is thereby substantially independent of the covering between the ties, and the latter are permitted to vibrate on the soft earth bed, providing necessary resiliency and preventing fracture of 15 the covering. The latter, being formed of concrete, of course maintains a hard surface at all times, and if this covering were continuous it would either be fractured or if heavy enough would destroy all resiliency. 20 In practice, a strip of sheet metal may be temporarily placed in position for forming the abrupt edge portions of the covering of the ties.

The bed being thoroughly protected, it 25 maintains its original condition indefinitely, the ballast, bed, and covering coöperating in the production of an ideal track construction. Furthermore, the creeping of the ties is prevented by the bracing effect of the 30 concrete between ties.

In addition to the use of a water-proof covering for the road bed, the surface of the bed is constructed in a novel manner. As shown, the spaces between the ties and 35 from the center of the track bed to the ends of the ties is given a compound slope in order to facilitate and secure the rapid and free drainage off of all rain water or other deposited moisture. To this end the portion 40 of the lower bed between the adjacent ties slopes from the inner sides of the ties, as indicated at 6 downwardly and inwardly to a point about centrally between the ties, as indicated at 7 whereby the sloping surfaces 45 meet each other in the form of a depression. From the longitudinal center of the space between adjacent ties, however, the surfaces 50 slope downwardly and outwardly from a point about level with the tops of the ties to a grade just above the bottom surfaces 55 of the ties, as indicated in Fig. 3, from which point the sides of the embankment forming the bed extend outwardly and downwardly in the form of sloping drainage surfaces 9, whereby the rain or other water is carried off for disposal. It will 60 thus be seen that the surfaces of the roadway between ties slope from a central point downwardly and inwardly between the ties and downwardly and outwardly from the 65 longitudinal center of the space between the ties, so that all moisture will be conducted away from the sides of the ties and in an outward and downward direction, thus keeping the ties and surrounding surfaces

at all times free from moisture. The rails 3 are also held supported above the level of the road bed and are thereby also protected from moisture, except as to the amount deposited directly thereon during a rain or 70 through the melting of the limited amount of snow which can fall thereon, or which may be deposited thereon naturally in the form of dew, with a result that the metallic parts of the trackway will be much less 75 subject to rust than the rails of track structures of the ordinary type. It will be observed that on account of the solidity of the road bed the use of rock or other ballast is entirely unnecessary, the ties being embedded 80 in the relative soft earth or other material and thus allowed to have a much greater resiliency or cushioning action than would otherwise be possible. Furthermore as the ground is protected from the soaking 85 effects of water, since all water will be immediately carried off and prevented from accumulating, it will be evident that the road bed will be at all times kept dry, solid and firm, and sponginess or loosening of the 90 earth with liability of the undermining of the track and spreading of the rails entirely obviated. The ties will also be effectually protected and prevented from decaying, thus adding to the preservative integrity of the 95 track structure as a whole. Other advantages are, that frequent critical inspection of the track is not necessary, and hence that the number of track walkers and section repair men may be reduced, that as all dust 100 and deposits are washed away by the rain water the raising of dust or grit by the passage of the rolling stock, with attendant inconveniences and disadvantages, will be wholly overcome. The parts of the track 105 will also be kept on perfect grade and in perfect alinement, and thus minimize danger of derailments, accidents, etc., while the cost of maintaining the tracks and rolling stock in repair will be materially reduced. Also there 110 will be less jar and vibration incident to the movement of the rolling stock, and the life of the rails will be greatly prolonged, because of the presence of a continuously dry road bed, and grass, weeds and like vegetable matter will be prevented from growing between rails, and danger of the ties catching fire from cinders will be entirely obviated, all of which will be appreciated by 115 those versed in the art. These and other advantages are obtained by the use of my improved road bed which will, within a brief time after construction, reduce the general cost of construction and maintenance, owing to the perfect condition in which the bed 120 and tracks remain and the reduction of repairs to the minimum.

I claim:

1. In a railway road bed and track construction, the combination of a bed of earth 130

or the like, ties and track rails laid thereon, and a covering of water-proof material including cement as an ingredient over the surface of the bed between and beyond the ties and rails and over the major portions of the ties, the edges of the portions over the ties meeting but being independent of those portions of the covering between the ties, permitting vibration of the rails and ties, said covering sloping at all points from the ties and beneath the intervening portions of the rails.

2. In a railway track bed and track construction, the combination of a bed of earth or the like, ties and track rails laid thereon, and a covering of a water-proof material including cement as an ingredient for the surface of the bed between and beyond the ties and rails and providing a substantially continuous covering for the bed and the ties, the vibratory movement of the ties being independent of the covering between the ties, said covering sloping outwardly and downwardly beyond the sides of the rails and being at the highest level on a longitudinal line centrally between the track rails and ties and thence sloping from the ties downwardly and inwardly and also

downwardly and outwardly beyond the ends of the ties.

3. In a railway bed and track construction, the combination of a bed of earth or the like, ties sunk into the bed to points just below the top surfaces thereof, said bed having outwardly and downwardly sloping surfaces beyond the sides of the rails and between adjacent sides of the ties, and having sloping surfaces between the longitudinal center of the road bed and the lateral sides thereof from the center of the road bed outwardly.

4. In a railway bed and track construction, a bed of soft earth, ties embedded therein at their central portion and having their ends partially projecting above the surface, and a covering of which cement forms an ingredient, presenting a permanent hard surface and laid in sections above the ties and bed, the surface being inclined in two directions with reference to the ties, and said sectional covering permitting vibratory movement of the ties on the bed without fracturing the covering.

In testimony whereof I affix my signature.

JAMES D. NEGUS.
